UNITED STATES PATENT OFFICE.

ALBERT R. PRITCHARD, OF ROCHESTER, NEW YORK.

HANDLE OR BAIL.

981,878.

Specification of Letters Patent. Patented Jan. 17, 1911.

Application filed March 17, 1908. Serial No. 421,714.

To all whom it may concern:

Be it known that I, ALBERT R. PRITCHARD, a citizen of the United States, and resident of Rochester, in the county of Monroe and 5 State of New York, have invented certain new and useful Improvements in Handles or Bails, of which the following is a specification.

This invention relates to handles or bails, 10 for sheet-metal vessels.

The object of the invention is to produce a strong, cheap handle ear, which may be applied to a vessel, such as a sheet metal wash boiler, etc., in such a manner that 15 the strain of lifting said vessel is borne, to a large extent, by the rim thereof, instead of by the weaker and thinner sides.

In the drawings:—Figure 1 is a side elevation of a vessel embodying this invention; 20 Fig. 2 is a perspective view of the ear; Fig. 3 is a vertical section on the line 3—3 of Fig. 2, showing the handle in place; and Fig. 4 is a perspective view of the parts shown in Fig. 2, but from the opposite side.

In Fig. 1 is shown a wash-boiler 1, having an outwardly projecting rim formed over a round wire 2 in the usual manner. The handle ear is formed of a piece of sheet metal 3, doubled upon itself in such a manner as to leave at the bend a tubular loop 3^a 25 adapted to receive a part of the handle 4. While the ear blank is flat, one or more tongues 5 are punched out, and are left standing up, as shown in Figs. 2 and 4, when the piece is bent outwardly from the back plate and doubled over around the handle 4 and forms the front plate 9 of the ear. The said tongues form part of the back plate 8 of the ear which lies in 30 contact with the side of the vessel. The front plate 9 in the example shown is fastened to the vessel by the same rivets that fasten the back plate thereto. The back plate 8 and the front plate or portion 9, 40 by which the loop 3^a is formed, are integral portions of the whole handle ear 3.

In fastening the ear upon the vessel 1,

it is pressed upward, so that the tongues 5 are jammed tightly between the sheet metal side of the vessel and the lower edge of the wire rim 2, (Fig. 3), and it is then fastened in that position by means of rivets 6, 6. The tongues of the back plate thus engage under the projecting rim where it meets the side of the vessel. 55

The handles 4 are of bail shape and are bent inwardly at the sides, so that the hand grasps 7, by reason of this bend, may come vertically above the loops or sockets and substantially in the plane of the back plate. 60 When the boiler 1 is lifted by means of said handles, the tongues 5, being pressed so closely against the rim 2, transmit the lifting strain vertically to the rim, and reduce that upon the sheet metal sides of the vessel and upon the rivets. Even when being carried by two persons, so that the direction of pull is at an angle to the vertical sides of the vessel, the strain comes almost entirely 65 upon the tongues 5 and rim wire 2. 70

By doubling the ear around the handle 4 as shown, a strong construction is obtained. Since the ear completely encircles the handle (Fig. 3), enough stock is left between the tongues 5 to give the necessary rigidity to 75 the structure.

What I claim is:—

The combination with a sheet metal vessel having the usual outwardly-projecting wire rim, of a handle ear consisting of a piece of sheet metal doubled upon itself to form at the bend a tubular loop 3^a adapted to receive the handle, and having a tongue 5 punched out from it and left standing up in the plane of the back piece of the ear, 80 adapted to jam between the wire rim and the side of the vessel; and the handle 4 bent inwardly to bring the hand grasp vertically over above the attaching ear; substantially as shown and described. 85

ALBERT R. PRITCHARD.
